(57) **CLAIM**

The ornamental design for a tire cover, as shown and described.

DESCRIPTION

FIG. 1 is a perspective view of a tire cover showing my new design;

FIG. 2 is a front elevational view thereof;

FIG. 3 is a back elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines shown illustrated on the tire cover represents stitching that forms part of the claimed design. The broken lines shown of the tire in FIGS. 3 and 7 represents environmental structure and form no part of the claimed design.

1 Claim, 7 Drawing Sheets
